No. 628,175.

J. O. BOWDISH.
KNOCKDOWN SHIPPING STALL.

Patented July 4, 1899.

(Application filed July 25, 1898.)

(No Model.)

UNITED STATES PATENT OFFICE.

JAMES O. BOWDISH, OF CINCINNATI, OHIO.

KNOCKDOWN SHIPPING-STALL.

SPECIFICATION forming part of Letters Patent No. 628,175, dated July 4, 1899.

Application filed July 26, 1898. Serial No. 686,787. (No model.)

To all whom it may concern:

Be it known that I, JAMES O. BOWDISH, a citizen of the United States, and a resident of Cincinnati, Hamilton county, State of Ohio, 5 have invented certain new and useful Improvements in Knockdown Shipping-Stalls; and I do hereby declare the following to be a clear, full, and exact description of the invention, such as will enable others skilled in 10 the art to which it appertains to make and use the same, attention being called to the accompanying drawings, with the reference-numerals marked thereon, which form a part of this specification.

15 This invention relates to improvements in collapsible stalls used for shipping horses in railway-cars. These stalls are particularly intended for cars which are only temporarily used for such purpose and in contradistinction to the regular stock-cars which are permanently fitted for such transportation. For such reasons it is desirable that these stalls are readily and conveniently set up when needed and quickly removed after use to clear 20 the car and render it available for other purposes. My invention relates to means and certain details of construction whereby these requirements are attained in a reliable and simple manner, combined with durability and 25 comparatively low manufacturing cost.

In the following specification, and particularly pointed out in the claims, is found a full description of the invention, its manner of use, parts, and construction, which latter is 30 also illustrated in the accompanying drawings, in which—

Figure 1 is a cross-section of a railway-car, showing front end of a section of stalls erected and filling the car across its width from side 40 to side. Fig. 2 is a longitudinal section of a stall, showing also one of the dividing-partitions in elevation. Fig. 3 is a vertical cross-section through one of the stalls of a section between its ends and particularly near the 45 rear end and looking toward the latter. Fig. 4 is an enlarged elevation, with the ends in section, of the adjustable retaining-rail, occupying when in place a horizontal position between the sides of the car which it engages 50 and constituting one of the parts for holding the partitions between the stalls in place. Fig. 5 is an enlarged elevation of one of these

partitions with parts broken away, showing also, partly in section, one of the uprights to which the front end of such partition connects. Fig. 6 is a top view, partly in section, of the parts shown in the preceding figure. Fig. 7 shows manner of temporary connection between the upright posts and the rail illustrated in Fig. 4.

These stalls are generally used in connection with so-called "express-cars" used by express companies in the transaction of their business and by means of which stalls such cars are temporarily converted into stock-cars, thereby enabling express companies to ship horses whenever called upon to do so. In the drawings, 10 indicates the floor, and 11 11 the sides of such a car. In beginning to build up a section of stalls for the temporary 70 use here in view the front sill 12 is first put down, being a flat iron rod of a length to fit readily between the sides of the narrowest car, it being understood that the cars are not all of the same width. The other parts resting on it tend to hold it practically in position, so that one or two nails 13 driven into the car-floor through holes 14 in these sills readily prevent their displacement. Next the front top rail 15 is placed in position vertically above this sill, the proper height being ascertained by putting temporarily one of the uprights 16 in place in a manner which will be presently understood. This top rail is preferably constructed of tubing or pipe 85 and carries at each end contact-plates 17 18, each provided with indenter-points adapted to enter the woodwork at the sides of the car when pressed thereagainst. The length of this rail 15 is adjustable, for which purpose 90 one of these plates—18 in this case—is carried on a screw 19, mounted in a stationary nut 21, which is permanently fixed in the adjoining end of the pipe. A hand-wheel 22, affixed to the screw, serves for moving the same, 95 with plate 18, in or out, by which means the length of rail 15 is adjusted to meet the width of the car and whereby also the necessary pressure is obtained to cause the indenter-points to bite into the wood. Plate 18 is 100 loosely carried at the end of screw 19, so that it does not partake of the rotation of the latter and whereby the indenter-points remain in position when once in engagement with

the wood, thereby preventing unnecessary injury and scratching of the same. 23 is simply a follower to guide the screw during its movement. The other plate 17 as to position 5 is permanently secured to the end of the pipe, being affixed to a plug 24, inserted thereinto, and rigidly connected. Uprights 16 are next placed in position. They are also formed of tubing or pipe and have at their lower ends 10 pins 25, projecting from plugs 26, permanently secured within the lower end of the pipe, and which pins are set into holes 27, formed in sill 12. At their upper ends are fork-shaped bearings 28, open at their upper 15 part, also permanently secured and fitted to embrace from below the retaining-rail 15. These uprights are placed in position in a manner shown in dotted lines in Fig. 1, which is by inserting pin 25 first in the proper hole 20 in sill 12, after which the upper end is swung over and slid in under rail 15, which is received by bearing 28 through the open upper part thereof until the upright assumes its proper vertical position. It is held so by a 25 locking-pin 29, dropped from above through a hole 31 in rail 15 and entering a hole 32 right below it in the bottom of bearing 28 at the upper end of the post. Pins 29 may be secured by chains 33 to prevent misplacement or loss. Partitions 34, constructed in 30 any suitable manner, are next placed in position. As shown, they consist of boards placed edgewise above each other and with their ends framed into and connected to upright frame- 35 pieces 35 and 36. The frame at the front end is higher than the partition itself, the excess of height being filled in by a triangular piece of open-work—as, for instance, wire-netting 30. From the front end of these partitions there 40 project outwardly headed pins 37, the heads of which are adapted to pass through openings 38 in uprights 16 if the partition is lifted sufficiently high, after which when the partition is lowered the shanks of these pins enter slots 45 39, starting from holes 38 downwardly. The weight of the partitions keeps these pins in place, while their larger heads prevent them from coming out endwise. The rear ends of the partitions are held in place below by pins 50 41, projecting downwardly and entering holes in sills 42, constructed and placed similar to sills 12. Above they are held by upwardly-projecting pins 43, which are received by 55 holes 44 in another retaining-rail 45, dropped over them. This latter rail is exactly con-

structed like rail 15 and also lengthwise adjustable in a manner to firmly engage the sides of the car, so that when in place the partitions are or should be held rigidly in position, and the erection of a section of stalls 60 is thereby completed. Of the pin-receiving holes in sills 12 and 42 and in retaining-rails 15 and 45 there is a number of each, perhaps an inch apart, to permit regulation of the width of the stalls to accommodate larger or 65 smaller horses. The rear ends of the stalls are closed by so-called "kicking-boards" 46, held in place by loops or hooks 47, which fit over retaining-rail 45 and on which these boards are supported. They may be preferably padded, as shown at 48. The front ends of the stalls are closed by a rail 49, held in place by brackets 51, projecting from uprights 16. If feed-boxes are required, they may be hung on these rails, as shown at 52. 70

After use the stalls may be quickly taken down in a manner which readily suggests itself and by performing the different manipulations mentioned in reverse order.

It will be noted that these stalls may be 80 manipulated without requiring any special tools or any particular skill or experience on the part of the persons handling them.

Having described my invention, I claim as new— 85

1. In knockdown shipping-stalls, the combination of the horizontally-disposed, removable floor-sill 12, provided with receiving-holes, the horizontally-disposed retaining-rail 15, upright posts 16 between them, a pin at 50 the lower end of each of these posts, adapted to engage the holes in the floor-sill, bearings at their upper ends to receive the retaining-rail, locking-pins to hold the bearings in position on the former and holes provided to 95 receive these pins.

2. In knockdown shipping-stalls, the combination of a horizontally-disposed retaining-rail, uprights 16 adapted to be alined therewith and locking-pins to hold them in place 100 below the retaining-rails, there being holes provided in the parts to be engaged adapted to receive said locking-pins when the engaging parts are in proper position.

In testimony whereof I hereunto affix my 105 signature in presence of two witnesses.

JAMES O. BOWDISH.
